(57) **CLAIM**

The ornamental design for a baby crib, as shown and described.

DESCRIPTION

FIG. 1 is a perspective view of the baby crib.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a perspective view of the baby crib, showing the frame separately for ease of disclosure.

The broken lines which define the bounds of the claimed design form no part thereof.
